LAUNDRY MACHINE

James N. White, Denver, Colo.

Application June 20, 1930, Serial No. 462,655,
and in Canada April 30, 1930

8 Claims. (Cl. 68—18)

This invention relates to cylinder laundry machines, and particularly to that class thereof in which there is a revolvably mounted cylindrical clothes container (hereinafter referred to as the "cage") having a partially cylindrical tub normally enclosing the lower part of the cage, for holding liquid to immerse such lower part.

An object of the invention is the improvement of a machine of said class in which the tub is partially, preferably about semi, cylindrical, and is in outside nested relation with the cage and is adapted to be revolved about the axis of the cage for either dumping the fluid or for uncovering the bottom of the cage to permit clothes to be dropped from the cage. Such a machine is described in my pending application, Serial No. 411,061, filed December 2, 1929, and the improvement of a machine such as that therein described and claimed is one of the objects hereof.

Further objects are the provision of improvement in the structure of the upper portion or cover, including associated parts, in the fluid-inlet structure, including associated parts, and in supporting and rotating mechanism for tubs of larger size.

The objects, including those above mentioned, will more fully appear from the following specification, as illustrated in the accompanying drawings, in which like characters of reference indicate corresponding parts throughout, and in which

Figure 1 is a front elevation, with portions broken away, of a machine of the smaller type, requiring driving mechanism for cage and rotating mechanism for tub at one end only. The fluid-inlet-assembly illustrated at the left of this figure need not be used complete where it is not adjacent driving mechanism, but is nevertheless shown complete in this figure.

Figure 2 is a section on line 2—2 of Fig. 1, showing the tub and associated parts in normal position for washing operation.

Figure 3 is a section on line 2—2 of Fig. 1, but showing the tub and associated parts in position at the extreme of the fluid-dumping movement.

Figure 4 is a section on line 2—2 of Fig. 1, but showing the tub and associated parts and the cage at the ends of their respective movements in the operation of dumping the clothes.

Figure 5 is a detail, partly in elevation and partly in section, of the fluid-inlet-assembly and associated parts.

Figure 6 is a vertical center section of the structure illustrated in Fig. 5.

Figure 7 is a fragmentary view of the inside of the end of the tub, showing the down-spout of the fluid-inlet-assembly.

Figure 8 is a section on line 8—8 of Fig. 6.

Figure 9 is a view in the same position as Fig. 8, but showing a modified structure of the fluid passages in the supporting member and bearing.

Figure 10 is a front elevation of a portion of a machine of the larger type, showing the improved fluid-inlet structure at one end and the improved tub-supporting and rotating structure at the center, the central portion of the machine being at the left of this figure.

Figure 11 is a view on line 11—11 of Fig. 10, giving a side elevation of the central supporting tub-rotating structure, indicating the tub in section and indicating the cage in dotted lines.

The machines will be described in terms of description of a washing machine, but, as with the machine described in my aforesaid pending application, the same may likewise be used for drying and for dyeing clothes, and may be used for various of these operations or parts of the operations, with the respective parts of the machine in various respective positions according to the requirements of the particular operation being performed, all of which will be apparent to those skilled in the art and in the performance of the operations of washing, rinsing, bluing, drying, dyeing, etc. No changes whatsoever in the structure here disclosed are necessary, and such changes as might be convenient for any of said operations would not affect the present invention and would be obvious to those skilled in the art. Therefore, the details of such various operations and obvious changes in structure will not be described herein.

It will also be understood that many changes may be made in details of the construction herein disclosed without departing from the spirit or substance of the invention and within the scope of the appended claims.

In suitable supporting members 1, which may be bolted to the floor as at 2, I provide bearings 3, having exterior bearing surface for the ring 4, of spider 5 affixed, as by bolts 6, to the disk 7', forming the end of the tub-and-cover-assembly hereinafter described, whereby the tub-and-cover-assembly is rotatable upon the bearing 3.

In the interior of the machine and in nested relation to the said tub and cover structure, I provide a cage 8, which may be of any suitable structure for such purpose, but which is here

shown as formed of wood staves, with fluid-inlet slots 9 therebetween. The cage is carried by gudgeons 10, rotatable in the bearings 3 and attached to the cage by any suitable means, as 5 by bolted plate 10a.

The tub 7 is carried by the disks 7' and may be formed integral therewith, as indicated at Fig. 1, the tub being preferably approximately semi-cylindrical, the rear edge thereof being 10 designated by the numeral 7a, and when the tub is in normal washing position it encloses the lower portion of the cage 8, as clearly shown at Fig. 2.

Partially enclosing the machine at the rear, I 15 provide a fluid guide 11a which may be supported by any suitable means, as by brace members 12. This guide extends upwardly to a point approximately at or slightly above the edge 7a of the tub in the position shown in Fig. 2, and 20 downwardly sufficiently to guide to the desired place any fluid escaping over the edge 7a, the same being here shown as extending to the bottom of the machine and terminating in an apron 13 for guiding such fluid to a drain or 25 trough 27.

Carried by the disks 7' in fixed relation to the tub 7, and preferably upon the same radius, I provide a cover member 14, having doorways and doors therein, as hereinafter described, the 30 portions of said cover adjacent said doorways consisting of bands 15, which comprise run-ways 16 for the doors hereinafter described, and which bands extend from the solid portion of the cover designated as 14 through the space occupied 35 by the doors to the stop 17 for the lower edge of the doors.

The cage 8 is revolved by means of power supplied from any suitable source to pulley 18, which conventionally indicates the common 40 three-pulley construction for imparting alternating rotation to the cage. This construction is standard, and only two pulleys are shown in Fig. 1. The three pulleys are shown in Fig. 10, but the construction is common knowledge to 45 those skilled in the art, and will not be further described except to say that in usual practice the driving belt shifts back and forth over the three pulleys so as to first rotate the cage a desired number of turns, usually two and one-half, in one direction, the direction of rotation being then reversed and the cage rotated a like number of times in the opposite direction, etc. The shaft 19 mounted for rotation in either direction in the bearings 20, carried on the upper 50 55 portions of supporting members 1, transmits power from the pulleys to the pinion 21, and thence to the driving gear 22 fixedly mounted on the end of the gudgeon 10.

Worm drive 23 is provided for rotating the 60 tub and associated parts and may be affixed to the spider 5 by any suitable means, as by extension 4a of the ring 4. The worm 24, carried and rotated by any suitable means, as motor 25, supported on bracket 26, meshes with the drive 65 23 and rotates the same in either direction, according to the direction of rotation of the motor 25, which, it will be understood, may be rotated in either direction, as desired.

The cage 8 is provided with doorways 28, normally 70 covered by sliding doors 29, while the spaces between the strips 15 of the cover 14 form doorways, which are normally covered by doors 30, sliding in the run-ways 16.

In order to supply washing, rinsing, bluing, 75 or other fluid to the interior of the tub 7 with-

out interruption of the operation of the machine, I provide means for conducting fluid into the interior of the tub through the bearing member 3, and between its interior bearing surface adjacent the gudgeon 10 and its exterior bearing surface adjacent the ring 4 and the inner edge of the disk 7'. This conduit is designated as 31, and the inner end thereof is inclosed by a suitable down-spout 32 of comparatively thin construction, so as to clear both the inner side of disk 7' and the bolted plate 10a. The thinness of the down-spout requires a compensating breadth thereof, as clearly shown in Fig. 7, in order to admit fluid in sufficient quantities and with sufficient rapidity. The down-spout has an opening 32a for admitting the fluid to the space between the cage 8 and the tub 7, as clearly shown at Fig. 5.

In constructing certain machines according to the present invention, parts of standard machines now in common use may be used, and many such machines have drive wheels for the cage at both ends of the machine, and some such machines have other mechanism which would render it difficult or impossible to enter 100 the bearing 3 with a conduit parallel to the gudgeon 10. Likewise, in constructing certain machines embodying the present invention, it would be found desirable to provide such drive wheels or other parts which would render it 105 difficult or impossible to enter the bearing from the outer end and in a line parallel to the gudgeon 10. In order to provide a suitable fluid-inlet for such cases, I form either an annular conduit 33 in the bearing, said conduit 110 connecting with the conduit 31, both as clearly shown at Figs. 1, 5, 6, and 8, and thread through the bearing a pipe 34 leading from any suitable source of supply and entering bearing 3 in the vertical plane of the supporting member 1, or I 115 provide a modified structure, as illustrated in Fig. 9, wherein pipe 34 connects with a conduit 35, formed in bearing support 36, and which conduit communicates with conduit 31 in the bearing.

When no drive wheel or other structure interferes with entering bearing 3 by a conduit parallel to the gudgeon 10, the conduit 31 may be extended to the outer end of the bearing, as indicated in dotted lines at 31a at the left of Fig. 1.

The operation of the structure disclosed in the first nine figures and described in the specification up to this point will now be described, but it will be understood that, so far as the 130 handling of clothes for washing, rinsing, bluing, drying, or any other operations is concerned, the structures disclosed in Figs. 10 and 11 and to be later described, operate the machine in just the same way, so far as the handling of the 135 clothes and fluid is concerned, as the operation which will now be described.

It will be understood by those skilled in the art of constructing, as well as by those familiar with the operation of, modern laundry machinery, that the handling of the clothes by the washing machine from the time the wash is commenced until the rinsing or bluing is completed, requires a number of successive changes of the fluid, and that these changes should be 145 made as quickly as possible, and that there should be as little as possible of interruption of the alternating of the clothes-containing cage, and that the time during which said cage is being operated without sufficient amount 150

of fluid in the tub to suitably support or float the clothes within the cage, should be reduced to the minimum. The operation of the cage without sufficient fluid in the tub is not only a waste of power and time, but tends to damage the clothes. Not only is it desirable to shorten to the minimum the period of time when there is less than the proper operating quantity of fluid within the tub, but a quick and effective elimination of the fluid from the tub is desirable also in order to rid the tub of dirt and settling. A slow drainage of the fluid leaves a considerable amount of settling in the tub and thus pollutes the next succeeding fluid or requires an intermediate rinsing of the tub.

My invention provides not only for the shortening to the minimum of the period when there is less than the proper operating quantity of fluid in the tub, but provides for the emptying of fluid from the tub in such a manner as to practically wash the tub and rid it of all dirt or settling.

Moreover, the emptying of the finished clothes from the tub has long been a serious problem in the development of modern washing machines, and many structures both expensive and inefficient have been resorted to for unloading the washing machine at the front. Unloading the machine at the front results in spilling the liquid dropping from the clothes onto the space occupied by the operator of the machine, which is usually also a passage-way for various operatives between rows of machines, and therefore any unloading of the machines from the front results in keeping such passage-way flooded and necessitates the use of water-proof coverings by the operatives, and results in a general splashing of the fluid on the operatives and adjacent apparatus, and in creating a general unsanitary condition.

For the purpose of loading dry clothes into the washing machine, it is desirable to raise the machine higher than the machines now in common use, because the operative can more easily load the machine if it is high enough so that he can stand upright in so doing. The raising of the machine to such height is, however, impractical with the means now in use, because the unloading operation as usually performed from the front of the machine could not be satisfactorily performed with the machine raised to the height which would be desirable for the loading operation.

It is obvious, also, that unloading wet clothes from a washing machine by any other means than by permitting such clothes to drop by gravity, requires a large amount of time and power, either human or machine, and an accompanying loss of time.

For the above, as well as for other reasons, which will be obvious to those skilled in the art, it is desirable to provide for the dropping of the clothes from the machine by gravity.

The quick and effective emptying of fluid from the machine, shortening the time when there is less than the proper operating quantity of fluid in the machine, and the emptying of the finished clothes solely by gravity and at the bottom of the machine are all accomplished by the structure disclosed in my aforesaid pending application, and likewise by the structure herein disclosed and claimed.

In operation, the cage 8 and the tub 7 are in position shown in Fig. 2, and in this position the doors 29 and 30 are open, thereby affording

free access to the interior of cage 8 through the doorways for loading the machine with clothes. The washing fluid is let into the tub 7 through the fluid-inlet means above described to the desired height in the tub, and preferably before the machine is loaded. When the machine is loaded, the doors 29 and 30 are closed and the cage is then rotated the desired number of times in each direction alternately as above described for washing the clothes in the washing fluid. When the operation in the first fluid has been carried on to the desired number of times, the motor 25 is operated to rotate the tub and associated parts forwardly to the position shown in Fig. 3. It will be understood that as the tub rotates the contained fluid will flow out over the edge 7a and will be caught by the flange 7b and guided to the inside of the guide member 11a, whence it will flow down over the apron 13 into the drain 27, and when the edge 7a reaches the bottom of the machine, the fluid will have been dumped from the machine so rapidly that the tub will have been substantially washed by the out-flow of the fluid. It will be understood that any suitable automatic reversing mechanism may be coordinated with the motor 25 whereby when the edge 7a has reached the desired point the motor will automatically reverse and rotate the tub and the associated parts back to the position shown in Fig. 2, and it will also be understood that the next successive supply of fluid may be admitted through the fluid-inlet means above described as soon as reverse rotation of the tub begins, so that the tub will be immediately filled to the desired height with fluid, thus shortening to the minimum the time when there is less than the desired amount of fluid within the tub.

In the ordinary handling of clothes, eight or ten successive fluids are commonly used for washing, rinsing, and bluing, and the saving of time and other advantages above described are accomplished at each one of the eight or ten successive operations.

When the handling of the clothes in the washing machine has been completed, and the clothes are ready to be removed therefrom, the doors 30 and 29 are opened, and the motor 25 is operated to rotate the tub to the position shown in Fig. 4, and the cage is also operated by its rotating mechanism to invert the cage to the position also shown in Fig. 4, whereupon the clothes are dropped by gravity from the cage through the doorways 28 and into any suitable receptacle which may be placed beneath the machine.

It will be noted that in this structure there are no pipes or valves or other projections from the bottom of the machine other than the apron 13, which may be positioned as far to the back of the machine as desired, so that a clear and unobstructed space is provided beneath the machine for the accommodation of any receptacle or conveying means into which it is desired to drop the clothes.

In machines of the larger type, it is desirable to provide supporting and rotating means for the tub and associated parts near the longitudinal center thereof, and my improved structure for this purpose is illustrated in Figs. 10 and 11, and while various changes in the details of said structure will occur to those skilled in the art and within the spirit and scope of this specification and the appended claims, the preferred form of such combined supporting and rotating structure is as illustrated in said figures, and con-

sists of a casting formed in three pieces, 37, 38, and 39, bolted together as at 40, 41, and 42, and encircling the machine. Suitable bearings on which the tub and associated parts may rotate are provided in the casting, as rollers 43. A band 44 is carried by the tub and associated parts encircling the same, and the band comprises a suitable element, as worm ring 45, for engagement with and actuation by another and power-transmitting element, as worm 46, carried by suitable bearings in the casting 39 and rotated in either direction, as desired, by automatic reversing motor 47 through pinion 48 and gear drive 49. In this preferred form, the band 44 comprises also a track 50 for bearing upon the rollers 43, and in this preferred form the track 50 is provided by splitting or grooving worm ring 45, thus forming a track in the center thereof. It will be understood that the relative position of the worm ring 45 and the track 50 may be changed as desired.

The edges 51 of the band 44 form a portion of the run-ways for the doors 30. In Fig. 11, the structure of the tub and associated parts, there indicated in cross-section, is illustrated only conventionally, and the details of the tub and associated parts as illustrated in this figure are to be considered only as conventional illustration in so far as they vary from the details of this structure, shown in Figs. 2 and 4. Likewise, in Fig. 11 the down-spout 32 is generally or conventionally illustrated, but the disclosure in this figure is not to be considered in so far as it differs from the disclosure in Figs. 1, 5, 6, 35 and 7, which are designed to show the preferred construction thereof.

The provision of the improved combined central supporting and rotating mechanism illustrated in Figs. 10 and 11 has many advantages, 40 which will be obvious to those skilled in the art, such as preventing the sagging of the central portion of the structure in the case of long machines, preventing the twisting of the tub and associated parts, which would tend to result 45 from the rotation of a long tub from one end only, and the obvious advantage of a single rotating mechanism in place of rotating mechanisms at both ends of the machine, which would be necessary for efficient and economical operation 50 of a long machine.

Flanges 52 may be provided for covering the sides of the worm ring, and thus more fully enclosing the same to prevent accidents to operatives and to guard against the entanglement 55 of articles in the ring as it is rotated.

I claim:

1. In a laundry machine having a clothes-containing rotatable cage, a substantially semi-cylindrical tub in outside nested relation to the 60 cage and rotatable about the axis of the cage, a substantially semi-cylindrical cover rotatable in fixed relation with the tub and having substantially the same radius as the tub, the cover and tub being spaced apart at the upper edge of the tub to permit fluid to escape over the edge of the tub, and a stationary guide member outside the tub and adjacent said upper edge of the tub and adapted to direct downwardly any fluid escaping over said edge of the tub.

2. In a laundry machine having a clothes-containing rotatable cage, a substantially semi-cylindrical tub in outside nested relation to the cage and rotatable about the axis of the cage, a substantially semi-cylindrical cover adapted to 75 rotate in fixed relation to the tub and having

substantially the same radius as the tub, said cover being spaced from the upper edge of the tub to permit fluid to escape over said edge of the tub and a member carried by said combined tub and cover and adapted to overlap said space between the edge of the tub and the cover whereby to direct downwardly fluid escaping over said edge.

80

3. In a laundry machine having a clothes-containing rotatable cage, a substantially semi-cylindrical tub in outside nested relation to the cage and rotatable about the axis of the cage, a substantially semi-cylindrical cover rotatable in fixed relation to the tub and having substantially the same radius as the tub, said cover being spaced from the upper edge of the tub to permit fluid to escape over said edge, a stationary guide member outside the tub and adjacent said upper edge of the tub and adapted to direct downwardly any fluid escaping over said edge of the tub, and a member carried by said combined tub and cover and adapted to guide any fluid escaping over said edge of the tub to a point within said stationary guide member.

85

4. In a laundry machine having a clothes-containing rotatable cage and a tub in outside nested relation to the cage and rotatable with, but independently of, the cage, means for rotating the tub and an approximately semi-cylindrical cover for the tub and cage carried by and 100 rotatable with the tub in fixed relation therewith, but spaced therefrom to form a slot for escape of fluid when the tub is rotated.

90

5. In a laundry machine having a clothes-containing rotatable cage, a rotatable cylindrical 110 casing in nested outside relation to the cage and including a tub and a cover portion spaced from the tub to form a fluid escape slot at the rear, doorways in the front portion of the cover, means for rotating the casing to bring said doorways to the bottom thereof for uncovering the under side of the cage, and means for rotating the cage to drop clothes from the cage through said doorways.

95

6. In a laundry machine having a clothes-containing rotatable cage, a rotatable cylindrical casing in nested outside relation to the cage and including a tub and a cover portion spaced from the tub to form a fluid escape slot at the rear, doorways in the cover portion, said tub normally 125 enclosing the lower part of the cage, and means for rotating the casing in either direction from said normal position to empty fluid through said slot when rotated in one direction and for bringing said doorways to the bottom for uncovering the under side of cage to permit clothes to be dropped from the cage through said doorways when the casing is rotated in the other direction.

100

7. In a laundry machine having a nested relation a rotatable clothes-containing cage and a 135 tub rotatable concentrically with the cage, a stationary bearing member having an inner bearing upon which said cage is adapted to rotate and an outer bearing upon which said tub is adapted to rotate, a bearing assembly including said stationary bearing member and a conduit entering the tub through said stationary bearing member between said inner and outer bearings and parallel to the axis of the tub and a supply pipe entering the bearing assembly at right angles to said conduit and communicating with said conduit within said assembly.

140

8. In a laundry machine having a cylindrical casing rotatably supported on roller supports and including a tub portion and a cover portion, 150

said cover portion being provided with runways and with doors slideable in said runways, the combination comprising a band encircling said casing and spaced from the cover portion to form the outer part of two of said runways, said band carrying, on its outer side, a track adapted to roll on said roller supports, said band also carrying means for engaging a power transmitting member, whereby to rotate said casing on said roller supports when power is transmitted through said member. 80 JAMES N.
